SNARE-DRUM.

1,142,843.

Specification of Letters Patent. Patented June 15, 1915.

Application filed July 26, 1911. Serial No. 640,575.

To all whom it may concern:

Be it known that I, ALFRED A. ROSE, a citizen of the United States, residing at Bellevue, in the county of Campbell and State of Kentucky, have invented new and useful Improvements in Snare-Drums, of which the following is a specification.

This invention relates more particularly to the snare drums of automatic musical instruments, such as pianos, organs, and orchestrions.

When such a drum is inclosed and placed near organ pipes, especially the flute-pipes, the sounding of the latter causes the snares to vibrate when the drum is silent and buzz unpleasantly by contact with the drum-head.

The object of my invention is to overcome this objection, and it consists essentially in mounting the snares on a support or carrier separate from the drum-head, and controlling the carrier by automatic means in such manner that the snares are withdrawn from the drum-head when the drum is silent and are moved against said head whenever the drum is played.

In the accompanying drawings: Figure 1 is a sectional elevation of a snare drum embodying the invention, showing the snare-carrier controlled by the pneumatic action of an automatic musical instrument, the snares being in their operative position. Fig. 2 is a rear view of the drum.

Similar letters of reference indicate corresponding parts in both views.

Fig. A indicates the body of the drum and B the drum-stick which may be vibrated by any suitable means but is preferably actuated by a pneumatic repeating mechanism controlled by a tracker board C and a perforated music sheet C¹. The preferred mechanism shown in the drawings is of a common type and comprises the motor pneumatic D, to the movable board of which the drum-stick is secured; the wind board E containing the suction chamber e; the valve chamber f connected with said suction chamber by a port f¹ and with the outer atmosphere by ports f²; the double valve g, g¹ controlling said ports and actuated by the

diaphragm g² in the suction chamber e; a passage h connecting the motor pneumatic with the valve chamber; ports i, i¹ leading from the top of the valve board E to opposite sides of the diaphragm g², and the slide valve i² controlling the last-named ports

and connected with the movable board of the motor pneumatic by a rod j. The suction chamber of the repeating mechanism is connected by tubes k, k¹ with the suction chamber L of the main wind chest L¹ of the 60 automatic musical instrument with which the drum is associated. This chest may be of any suitable or well known construction, that illustrated in the drawings containing the usual valve chamber l connected by 65 ports l¹ with the suction chamber L and by ports l² with a chamber l³ leading to the outer atmosphere; the valves m, m¹ controlling the ports l¹, l², respectively, and the diaphragm or pneumatic m² for operating 70 said valves. The chamber beneath this diaphragm is connected by a tube m³ with the corresponding duct of the tracker board, so that whenever a drum-perforation of the music sheet registers with said duct the 75 vibrating or repeating mechanism of the drum-stick is actuated, while under other conditions said mechanism remains at rest, in a manner well understood by those skilled in the art.

N indicates the snares of the drum which instead of being stretched over the drum-head, are mounted on the front side of a support or carrier o movable toward and from the drum-head to shift the group of 80 snares into or out of contact therewith. This carrier preferably consists of a bar extending diametrically across the drum head at a short distance therefrom and pivotally attached at one end to the rear hoop of the 85 drum by hooks o¹ and eyes o², or other suitable means. The carrier is provided at its ends with nuts or bridges o³, o⁴ over which the snares are stretched.

At one end the snares are suitably secured 90 to the carrier, while their other ends are attached to or clamped in a follower p connected to a tightening device, preferably consisting of a longitudinal screw q. This screw engages a threaded opening in said 100 follower and is journaled in a bearing or cleat r secured to the back of the carrier, the head of the screw having a cross pin q¹ or other suitable means for turning it.

As shown in Fig. 1, the drum is preferably supported in an inclined position, so that when the snare-carrier is released it hangs in a vertical position in which the snares are out of contact with the drum head, as shown by dotted lines.

S indicates a motor pneumatic adapted to swing the snare-carrier forwardly to press the snares against the drum-head when the drum is played. In the embodiment of the invention shown in the drawings, this pneumatic is mounted vertically on the rear side of the wind board E and the arm s of its movable board carries an adjustable screw s^1 the headed end of which is arranged to bear against the rear side of the snare-carrier at or near its free lower end, so as to swing the snares against the drum-head when said pneumatic is collapsed, as shown by full lines in Fig. 1. This pneumatic is preferably combined with and controlled by the same pneumatic action which controls the operating devices of the drum-stick, but I do not wish to be limited to that particular type of mechanism or the details shown in the drawings, as the same may be modified without departing from the spirit of the invention. In the construction shown, the interior of the pneumatic S is connected with the valve chamber l of the wind chest L¹ by the tube h and a branch tube t.

The operation of the device is as follows: When a drum-perforation of the music sheet registers with the corresponding tracker duct, the outer atmosphere raises the diaphragm m^2 of the main wind chest, shifting the valves m , m^1 to the position shown in the drawings. The suction chamber e of the repeating mechanism is thereby placed in communication with the suction chamber L of the main wind chest, causing the motor pneumatic D and the drum stick to vibrate so long as the valves m , m^1 remain in that position, in a well known manner. At the same time, the pneumatic S is collapsed, causing its movable board to swing the snare-carrier o forwardly and bringing the snares into their operative position. When a drum perforation of the music sheet breaks register with the tracker duct, the position of the wind chest valves m , m^1 is reversed in a well known manner, cutting off communication between the suction chamber L of said chest and the corresponding chamber e of the repeating mechanism and allowing the drum stick to remain at rest. At the same time the pneumatic S is flushed, withdrawing the screw s^1 from the snare-carrier and allowing the latter to recede to the dotted position shown in Fig. 1. In this position, the snares are wholly out of contact with the drum head and any sympathetic vibration of the snares cannot therefore produce the objectionable sounds hereinbefore referred to. When the next drum-perforation of the music sheet comes into action, the snares are again shifted against the drum head, as before described.

The improvement can be readily applied to ordinary snare-drums and as the actuating devices of the snare-carrier may be com-

bined with the pneumatic action of the musical instrument, the use of the invention involves but slight additional cost.

I claim as my invention:

1. The combination of a drum, a support movable toward and from the drum-head, snares mounted on said support, and automatic means for moving said support to press the snares against the drum-head when the drum is played and to withdraw the snares from the drum-head when the drum is silent.

2. The combination of a drum, a support movable toward and from the drum-head, snares mounted on said support, and pneumatic means for actuating said support.

3. The combination of the body of a drum, a carrier extending across the head of the drum and pivoted at one end to the body to swing toward and from the drum-head, snares mounted on the inner side of said carrier, and means for swinging the carrier toward the drum-head.

4. The combination of the body of a drum supported in an inclined position, a carrier extending across the head of the drum and pivoted at its upper end to the body to swing toward and from the drum-head, snares mounted on the inner side of said carrier, and means for swinging the carrier toward the drum-head.

5. The combination of the body of a drum, a carrier extending across the head of the drum and pivoted at one end to the body to swing toward and from the drum-head, snares mounted on the inner side of said carrier, and a pneumatic arranged to act on the free end of the carrier to press the snares against the drum-head.

6. The combination of the body of a drum, a carrying bar extending diametrically across the head of the drum and pivoted at one end to the body to swing toward and from the drum-head, snares stretched over the face of said bar, and means for holding said bar against the drum-head.

7. The combination of the body of a drum, a carrying bar extending diametrically across the head of the drum and pivoted at one end to the body to swing toward and from the drum-head, snares stretched over the face of said bar, a motor pneumatic, and an adjustable screw carried by the movable member of said pneumatic and arranged to bear against the rear side of said bar.

8. The combination of a drum, a support movable toward and from the head of the drum, snares carried by said support and facing the drum-head, a follower mounted on said carrier and connected to one end of the snares, and a tightening screw journaled on the carrier and engaging said follower.

9. The combination of a drum, a drum-stick, pneumatic actuating mechanism for said stick, a carrier movable toward and

from the drum-head, snares mounted on the face of said carrier, pneumatic mechanism for actuating the snare-carrier, and automatic controlling means for both said actuating mechanisms constructed to withdraw the snare-carrier to its inoperative position when the drum is silent and to project the same to its operative position when the drum is played.

10 10. The combination of a drum, a drum stick, actuating mechanism for said stick, a carrier movable toward and from the drum head, snares mounted on said carrier, mech-

anism for actuating the snare-carrier, and automatic controlling means for both said actuating mechanisms constructed to withdraw the snare-carrier to its inoperative position when the drum is silent and to advance said carrier to its operative position when the drum is played.

15 20 Witness my hand this 14th day of July, 1911.
